UNITED STATES PATENT OFFICE

2,477,961

PAPER ROLL HOLDER

Melville F. Campbell, Springfield, Mass.

Application March 9, 1946, Serial No. 653,369

1 Claim. (Cl. 242—55.2)

1

This invention relates to improvements in roll holders and is directed more particularly to improvements in holders for rolls of toilet paper, facial tissue, paper towels and the like.

The principal objects of the invention are directed to the provision of a roll holder which is made from a single length of material so as to be economical to manufacture and which is constructed and arranged to support a roll for rotation on a horizontal axis spaced from and in parallelism with a vertical wall.

According to special features of the invention, the holder is constructed and arranged without relatively movable parts so that a roll may be slipped thereonto and the hollow core removed therefrom yet while a roll is in rotative position on the holder it is prevented from displacement therefrom and is frictionally held against rotation so as to prevent waste of the paper of the roll.

With the foregoing and various other novel features and advantages and other objects of my invention as will become more apparent as the description proceeds, the invention consists in certain novel features of construction and in the combination and arrangement of parts as will be hereinafter more particularly pointed out in the claims hereunto annexed and more fully described and referred to in connection with the accompanying drawings wherein:

Fig. 1 is a front elevational view of a holder embodying the novel features of the invention and having a roll of paper associated therewith;

Fig. 2 is an end elevational view of the holder shown in Fig. 1; and

Fig. 3 is a small scale plan view of the holder shown in Figs. 1 and 2.

Referring now to the drawings more in detail, the invention will be fully described.

The holder of the invention is made from a single length of material such as wire and is bent or formed by a bending or forming machine to have the related elements to be described.

A rear horizontal wall member 2 for engaging a vertical wall has its inner end formed to provide upper and lower loops or eyes 4 and 6 connected by a portion 5.

Screws such as 10 may be passed through the eyes 4 and 6 into a vertical wall such as 12 whereby the holder is rigidly secured to said wall.

From the outer end of the member 2 there extends at right angles relative thereto and in a horizontal plane a spacer member 14.

A roll supporting member 16 extends from the outer end of the member 14 which is in the same

horizontal plane as the members 2 and 14 and is spaced from and in parallelism with said member 2.

The extremity of the member 16 is bent to form a loop 18 which is disposed above the plane of the roll supporting member 16.

Said loop preferably has a vertically disposed member 20 for engaging one end of a roll of paper, a horizontal member 22, an outer vertical member 24 and a terminal member 26.

A roll of paper is represented by 28 from which the web of paper 30 depends and it has the usual hollow core 32.

The vertical dimension of the loop 18 is such that the core 32 of the paper roll may be passed thereover and onto the roll supporting member 16.

The roll 28 is rotatable on the member 16 but is held from displacement therefrom by the loop 18 which is disposed upwardly from said member 16.

The member 16 may be of any desired length to accommodate rolls of various widths. However, the distance between the spacer member 14 and the vertical member 20 will be such that opposite ends of the roll are frictionally engaged thereby to prevent spinning of the roll as the web is being unwound for tearing off sections thereof.

The roll is supported for rotation on a horizontal axis which is parallel to the wall so as to occupy a minimum of space and while the roll may be rotated by pulling on the web it is frictionally held by the members 14 and 20.

The roll is easily and readily placed on the holder by passing the core over the loop by which it is held in relative position.

The invention may be embodied in other specific forms without departing from the essential characteristics thereof. Hence, the present embodiments are therefore to be considered in all respects merely as being illustrative and not as being restrictive, the scope of the invention being indicated by the appended claim rather than by the foregoing description, and all modifications and variations as fall within the meaning and purview and range of equivalency of the appended claim are therefore intended to be embraced therein.

What it is desired to claim and secure by Letters 50 Patent of the United States is:

A paper roll holder comprising in combination, a single length of wire bent to have a wall engaging portion and a spacer portion extending therefrom and from which extends a roll supporting member terminating in a loop, said wall

engaging portion having a downwardly depending portion formed to provide spaced loops for screws for holding the holder to a wall, said spacer portion extending at right angles from said wall engaging portion, said wall engaging portion and spacer portion and roll supporting member being in the same horizontal plane with said roll supporting member being in parallelism with said wall engaging portion and said loop being disposed upwardly from the plane of said roll supporting member; and said spacer member and said loop being spaced apart to receive therebetween a roll of paper on said roll supporting member and adapted to frictionally engage therebetween opposite ends of the roll.
